COMBINED CLOCK AND ADVERTISING DISPLAY
OR SIMILAR ARTICLE

George Nelson, New York, N. Y., assignor to Self Wind-
ing Clock Company, Inc., a corporation of Delaware

Application August 21, 1957, Serial No. 47,468

Term of patent 14 years

(Cl. D1—12)

FIG. 1

FIG. 2

FIG. 3

FIG. 4

FIG. 6

Fig. 1 is a perspective view of a combined clock and advertising display, showing my new design;

Fig. 2 is a front elevational view thereof;

Fig. 3 is an end elevation thereof, viewed from the right of Fig. 2;

Fig. 4 is an end elevation thereof, viewed from the left of Fig. 2;

Fig. 5 is a top plan view thereof; and

Fig. 6 is a bottom plan view thereof.

The dominant features of my design reside in the full line portions of the drawing.

I claim:

The ornamental design for combined clock and advertising display or similar article, as shown and described.
